UNITED STATES PATENT OFFICE.

ROBERT P. ORR, OF ALBANY, NEW YORK.

CARRIER-RECEPTACLE.

1,340,077.

Specification of Letters Patent. Patented May 11, 1920.

Application filed April 5, 1919. Serial No. 287,793.

To all whom it may concern:

Be it known that I, ROBERT P. ORR, a citizen of the United States, and a resident of Albany, in the county of Albany and 5 State of New York, have invented a new and Improved Carrier-Receptacle, of which the following is a full, clear, and exact description.

This invention relates to receptacles used 10 for carrying different articles, and has for an object the provision of an improved carrier receptacle which may be easily supported while at the same time arranged to present easy access.

15 Another object of the invention is to provide a carrier receptacle for mail carriers, soldiers, and for other parties desiring an easy means for carrying one or more articles.

20 A further object is to provide a carrier with a number of compartments and straps or other supporting means associated with a yoke whereby the weight of the carrier and its contents may be carried by both 25 shoulders.

In the accompanying drawing:

Figure 1 is a view of a figure with an embodiment of the invention shown thereon.

Fig. 2 is a top plan view of the carrier 30 shown in Fig. 1, certain parts being shown in section.

Fig. 3 is a fragmentary sectional view through Fig. 2 on line 3—3.

Fig. 4 is a transverse fragmentary sectional view through Fig. 2 on line 4—4.

Referring to the accompanying drawing by numerals, 1 indicates a yoke which is provided with pressed out portions 2 on each shoulder so as to prevent the straps 3 and 4 from slipping off the shoulders when in use. If desired the yoke 1 could be arranged beneath the coat and the projections 2 would act properly for holding the straps in place. The straps 3 and 4 45 may be connected by stitching, rivets, or otherwise to the body 5 of the carrier.

The body 5 of the carrier as shown in Fig. 2 is made up of a number of compartments, there being six compartments shown, 50 though a greater or less number may be provided without departing from the spirit of the invention. It will be observed that compartments 6, 7 and 8 are positioned to be on one side of the person using the de-

vice and compartments 9 and 10 on the 55 opposite side of the person, compartments 6 and 8 being connected by extensions 11 and 12 of the compartments, or if desired by straps. These extensions are connected together by a snap fastener or other securing means 13. The compartments 8 and 10 are connected together by any suitable means, as for instance a strap and buckle 14 whereby they may be quickly and easily disengaged when removing the device. The 60 various compartments 6, 7 and 8 are preferably made from two pieces of material 15 and 16 and divided into compartments by collapsible partitions 17 and 18. Collapsible end members 19 and 20 are provided 65 also similar in structure to the partitions so that the compartments will be independently collapsible and provided with the same side members. The side members 15 and 16 and also the partitions may be made 70 from canvas, leather or other suitable material. A bottom member 21 is provided for the various compartments, which may be an extension of one of the side members, or may be a separate piece secured in place. 75 The various compartments 8, 9 and 10 are constructed identically with compartments 6, 7 and 8 and will need no additional description. If desired reinforcing members 22 and 23 may be arranged in the compartments, as for instance the respective compartments 8 and 10. These reinforcing 80 members are arranged to reinforce the compartments vertically as well as longitudinally without interfering with the collapsing of any compartment. In addition each of the compartments is provided with a flap or cover 24 which may be formed as an extension of the side or may be made 85 separate and secured in place. These flaps or covers are held closed normally by snap fasteners or any other desired means, preferably arranged on the inner part of the carrier so that the flap may be opened outwardly as shown in Fig. 1 and thereby allow a person to secure access to the compartments by using only one hand.

The arrangement of compartments, in fact the entire arrangement of carrier, which is supported by yoke 1 is such that 105 a comparatively heavy weight and also a comparatively large number of articles may be carried with ease. This is of special

advantage to mail carriers or peddlers where at different times a large number of articles are to be carried and access thereto is desired quite often. The arrangement of flap 24 permits ready access while at the same time presenting loss against accidental displacement. If desired for special purposes a large number of small compartments could be provided or only a single compartment on each side. In some cases it might be desirable for use by soldiers for carrying their usual required articles and if desired could be arranged to receive the usual roll now in common vogue. Where a soldier's roll was to be carried in this man-

ner a number of buckles or straps could be provided for holding the same in place.

What I claim is:

A carrier receptacle, comprising a circular body divided into two parts, each part consisting of substantially concentric inner and outer walls having a bottom connecting them, said walls forming continuous smooth surfaces throughout their length, a plurality of collapsible partitions connecting the inner and outer walls, dividing the body into compartments, and each compartment having a separate cover. 25

ROBERT P. ORR.
